PLASTICS INJECTION MOLDER

Robert M. Haygeman, Box 11, Canton, S. Dak. 57013

Filed May 3, 1973, Ser. No. 356,744

Term of patent 14 years

Int. Cl. D15—99
U.S. Cl. D55—1 F

FIG. 1 is an isometric view of my plastics injection molder;

FIG. 2 is a side view thereof;

FIG. 3 is a side view thereof taken from the right side of FIG. 2;

FIG. 4 is a bottom view thereof; and

FIG. 5 is a top view thereof.

I claim:

The ornamental design for a plastics injection molder, as shown.
